CLAIM

The ornamental design for a vehicle oil drip pan or the like, as shown and described.

DESCRIPTION

FIG. 1 is a front elevational view of a vehicle oil drip pan or the like showing my new design, the rear view being a mirror image;

FIG. 2 is a left side elevational view thereof, the right side view being a mirror image;

FIG. 3 is a top plan view thereof; and,

FIG. 4 is a top perspective view thereof.
